DESIGN FOR A PLAY TABLE OR THE LIKE

Jacob Pressman, New York, N. Y.

Application March 15, 1940, Serial No. 90,934

Term of patent 7 years

To all whom it may concern:

Be it known that I, Jacob Pressman, a citizen of the United States and a resident of the city of New York, Borough of Manhattan, in the county and State of New York, have invented the new, original, and ornamental Design for a Play Table or the like of which the following is a specification, reference being had to the accompanying drawing, forming part thereof, in which—

Fig. 1 is a perspective view of a play table showing my design;

Fig. 2 is a plan view of the table; and

Fig. 3 is a side elevational view of the table.

I claim:

The ornamental design for a play table or the like, substantially as shown.

JACOB PRESSMAN.
